BLADE SHARPENER

Walter Struve, Mineola, N. Y.

Application December 29, 1944, Serial No. 570,367

1 Claim. (Cl. 51—72)

This invention relates to razor blade strops of the rotary type.

The principal object of the present invention is to provide a rotary razor blade strop which is of the simplest construction which may be made to sell for a nominal sum and which may be used by the general public without prior instruction or practice.

Another object is to provide a rotary razor blade strop which comprises but three parts—a frame, 10 a roller and a crank—the crank and roller being readily removable from the frame for cleaning purposes.

A further object is the provision of a rotary razor blade strop of the character described, having a crank which may be rotated on an axis which intersects the longitudinal axis of the roller in order to enable the crank to assume a non-projecting position against the side of the frame when the device is not being used.

Still another object is the provision of a rotary razor blade strop of the character described in which the roller comprises a unitary member which possesses abrasive properties not only on its surface but throughout.

These and other objects are attained by mechanism illustrated in the accompanying drawing in which—

Fig. 1 is a perspective view of the assembled device showing a razor blade mounted on the platform of the device in stropping position against the roller;

Fig. 2 is a transverse vertical section of the device shown in Fig. 1 showing how the finger of the operator rests against the side of the blade during the stropping operation; and

Fig. 3 is a longitudinal vertical section of the device shown in Fig. 1 on the line 3—3 of Fig. 1.

Referring to the drawing, the rotary razor blade strop herein claimed comprises a unitary frame 10 which is boxlike in shape and which has two upwardly extending flanges or shoulders 11 formed at its two end portions. These flanges serve as guides for the razor blade which is supported, during the stropping operation, on that portion of the frame which lies between said flanges, which portion will hereinafter be referred to as the blade supporting platform 12 of the device. A longitudinal extending hole 13 is formed adjacent one of the upper side edges of 50 said frame, extending through the two flanges 11 and the blade supporting platform 12. It will be seen in the drawing that said hole takes the form of a concave groove or trough in the platform proper between the two flanges.

The roller 14 comprises a unitary member which is adapted to be rotatably mounted within hole 13. It will be seen in Fig. 3 that the length of the roller extends the length of the frame and that it projects outwardly at both ends of the frame. A unitary crank 15, which is simply an L-shaped member, circular in cross section, is rotatably carried by the roller at one projecting end thereof, an enlarged head portion 16 on said crank prevents removal thereof from the roller. It will be observed that in view of the circular cross sectional shape of said crank, it is possible to rotate or pivot said crank on an axis which intersects the longitudinal axis of the roller at right angles. This renders it possible to "fold" the crank against the end portion of the frame when the device is not in use.

It will be observed, too, that the roller is readily removable from the frame by the simple expedient of withdrawing it axially from hole 13 in which it is normally disposed.

To use the device, the blade is placed upon its platform between flanges 11 as shown in Fig. 1. The edge of the blade to be sharpened is placed 25 against the surface of the roller, pressure contact therewith being maintained by the finger resting against the blade and gently urging it in the direction of the roller. It will be noted in Fig. 2 that the angle at which the platform meets the roller is predetermined to provide the proper angular relationship between the blade mounted on said platform, and the roller for proper stropping operation. The blade edge is sharpened by 30 simply turning the crank handle and thereby rotating the roller with which said edge is in contact.

It is intended that the frame be made of a unitary piece of material such as plastic material, molded to the shape shown and described. Any 40 other suitable material, such as wood, may also be used. The roller should be made of a unitary piece of leather. Such leather is available on the open market in normal times in the form of sewing machine belting having a circular cross sectional shape. It has all of the desirable abrasive properties. The crank is intended to be made of a unitary piece of metal wire. Plastic may also be used.

It is clear from the foregoing that the present invention is practical in all respects, being inexpensive to make, compact, simple to use and easy to clean.

I claim:

A rotary razor blade strop comprising a blade 55 supporting platform, upwardly extending flanges

on opposite ends of said platform to position the blade, a pair of registering holes in said flanges, said holes extending partly above and partly below the top of said platform between said flanges and extending across the top of said platform in the form of a concave groove, a roller having an abrasive surface, said roller being of uniform cross section throughout and being rotatably mounted within said flange holes and said groove,

and a crank affixed to one end of said roller for rotating the same, said crank being pivotally fixed in said roller on an axis which intersects the longitudinal axis of the roller at right angles to enable said crank to assume a non-projecting position against the platform when the strop is not in use.

WALTER STRUVE.
